INVALID BED

Anton Dishmaker, Fond du Lac, Wis.

Application August 6, 1942, Serial No. 453,871

9 Claims. (Cl. 5—90)

This invention relates to invalid beds the mattress support of which is so constructed and arranged as to be adjusted out of a horizontal plane, and more particularly to invalid beds of the general type in which a bed pan carrier is associated with the bed structure and movable by mechanical means into and out of a position of service with respect to the mattress support.

An important object of my invention is to provide an invalid bed having adjustable sections or wings and means for conveniently and expeditiously adjusting the wings to various positions according to the needs or desires of the patient occupying the bed.

Another object of my invention is to provide in an invalid bed of the above character, a mattress support capable of being adjusted out of a horizontal plane by the bed attendant for raising the patient from a reclining to a sitting position, together with a bed-pan carrying arm movably associated with the bed and operable by the attendant for traversing the pan into and out of its position of use.

In the preferred form of my invention the mattress support is made up of a plurality of hinged wings adapted to normally lie in a horizontal plane but certain of the wings being swingable to provide a back support and a leg support for the patient when the latter is moved to a sitting position. By virtue of this construction, the patient may be quickly and easily raised with comparatively little effort on the part of the attendant and the pan may be quickly shifted into place so that it may be employed in a natural and convenient manner. My bed is especially suitable for those patients who are required to wear plaster casts, harness or splints and because of which the use of the bed pan ordinarily provided in hospitals is extremely difficult and unsatisfactory.

Another object of my invention is to provide a bed pan carrying arm adapted to be collapsed and folded against the foot end of the bed frame in an out-of-the-way position but capable of being promptly brought into service, as occasion demands in proper relation to the patient without necessitating the removal of the bed covers.

Other objects and advantages will be apparent from the following detailed description of a preferred embodiment of the invention, reference being had to the annexed drawings in which:

Figure 1 is a longitudinal, sectional view taken through the frame of my invalid bed showing my improved sectional mattress support and the means for adjusting the sections thereof in side elevation;

Figure 2 is an isolated perspective view of the mattress support of the bed of Fig. 1 showing its hinged wings and various positions which said wings are adapted to assume;

5 Figure 3 is a detailed view of a hand-crank used for adjusting the position of the mattress support;

Figure 4 is a detailed perspective view of the bed pan carrier shown in its nested or collapsed condition when not in use at the foot of the bed;

10 Figure 5 is a plan view of the bed pan carrier in extended position with the cover of the housing partly removed;

Figure 6 is a side view of the bed pan carrier of 15 Fig. 5;

Figure 7 is a transverse cross-sectional view of the bed pan carrier taken on the line 7—7 of Fig. 6; and

20 Figure 8 is a detailed cross-sectional view 20 through the bed pan and its supporting platform.

In Fig. 1 is shown in cross-section an invalid bed comprising a head-end frame, a foot-end frame 2, and a pair of side rails 3 extending along opposite sides of the bed and connecting the 25 head-end and foot-end frames in the usual manner. Disposed at an elevation a slight distance above the plane of the side rails is a mattress support 4. This mattress support consists of a rectangular frame 5, of a width somewhat less 30 than the distance between the side rails 3, to which a wire fabric 6 is yieldably connected. The mattress support is of sectional construction and comprises four hinged sections or wings, namely a head wing 7, a fixed wing 8 secured to the side 35 rails 3, a movable intermediate foot wing 9 and a terminal wing 10. A mattress M, indicated in dotted lines in Fig. 1, is adapted to overlie the mattress support in the customary manner.

The wings are arranged to be adjusted by the 40 following mechanism: Suitably supported from one of the side rails 3 is a rotatable operating shaft 11. This shaft at the foot end of the bed is journaled in an ear and projects outwardly from one of the legs of the bed frame 2 and 45 is provided with a hand-crank 12 for turning the shaft. This shaft at its opposite end is provided with a worm 13 which engages a worm-wheel 14. The worm wheel 14 is secured to an end of a shaft 15 extending crosswise of the bed a short distance below the fixed intermediate wing 8 and 50 rotatably supported in brackets 16 depending from the side rails 3. Keyed to the shaft 15 adjacent its ends is a pair of arms 17 which are pivotally connected at their outer ends to links 55 18, which links in turn are pivotally connected

to the frame 5 of the head wing 7. The head wing is hinged at 19 to the forward end of the fixed intermediate wing 8 so that by turning the hand crank 12, shaft 15 is rotated by means of worm wheel 14 to raise or lower the head wing as a result of the push or pull exerted by the carrier arms 17 on the links 18. One position of adjustment of the head wing is shown in Fig. 1 and another in the dotted line position of Fig. 2. This elevates the back of the occupant of the bed. One of the brackets 16 is formed in a manner such as to provide a housing for the worm 13 and worm wheel 14, and this also serves to support the worm end of the shaft 11.

Upon the opposite side of the bed from the operating shaft 11 is a similar operating shaft 20, this latter shaft extending below and parallel to the other side rail 3. Shaft 20 is journaled in an ear projecting outwardly from the associated leg of the bed frame 2 and on its projecting end carries a hand-crank 21 for turning the shaft. A worm 22 is secured to the other end of the shaft and this worm meshes with a worm wheel 23 secured to one end of a shaft 24. Shaft 24 extends crosswise of the bed at an elevation below the fixed intermediate wing 8 and is rotatably supported in brackets 25 projecting downwardly from the side rails 3, one of these brackets providing a housing for the worm and worm wheel and a support for the worm end of the shaft. A pair of arms 26 keyed to shaft 24 are at their outer ends pivotally connected to links 27 by means of pins 28 which links in turn are pivotally connected to the terminal foot wing 10 of the frame 5 by means of pins 29. By virtue of this construction when the crank 21 is operated, the arms 26 exert a push or pull upon the links 27 to swing the terminal foot wing 10 about its hinged connection 19a with the movable intermediate wing 9, and also to rock the latter wing about its hinged connection with the fixed intermediate wing 8.

Turning the crank 21 under any circumstances will swing the movable intermediate wing 9 about its pivotal connection with the fixed intermediate wing 8. The angle assumed by the terminal wing 10 with respect to the wing 9 is governed by the following mechanism: Extending between the arms 26 and the terminal foot wing 10 are links 30. The links 30 are pivotally connected at their upper ends to the wing 10 by means of a cross rod 32. The lower ends of the links 30 are pivotally connected to the arms 26 by pivot pins 31. The cross rod 32 extends through slots 33 formed in the sides of the foot wing 10. The relationship of the links 30 to the terminal foot wing is such that when the links and the associated cross rod 32 abutting the forward end of the slots 33 (the left-hand end in Fig. 1) the terminal foot wing will "break" forwardly, as indicated at A in Fig. 2, when the arms 26 are lowered. When the links 30 are positioned with the cross rod abut the rear end of the slots (the right-hand end in Fig. 1) the terminal foot wing 10 will break rearwardly, as indicated at B, when the arms are lowered to move the wings 9 and 10 out of a horizontal plane. These wings may also be caused to assume the position C when the crank 21 and associated gear is turned so as to raise the wing 9 above the plane of the bed. Also by suitably positioning the links 30 both of the wings 9 and 10 may be tilted in a common plane, as indicated at D.

Positioning the links 30 anywhere between the two extreme limits of adjustment as determined

by the length of the slots 33 effects a corresponding reduction in the sharpness of the forward or rearward break (that is the angular relationship between wing 10 and wing 9) which occurs in lowering the wings out of horizontal position. One selected position of adjustment of the mattress support is shown in full lines in Fig. 2, and it will be appreciated that the adjustment of the inclination of the wing 10 and wing 9 is subject to wide variation. For accomplishing such adjustment, there is provided a control mechanism comprising a screw-threaded shaft 34 rotatably supported within a bracket 35 depending from the rear end of the terminal wing 10 at the foot of the bed. The end of the shaft 34 projecting outwardly beyond the bracket is provided with a hand-crank 37 for manually turning the shaft 34. The inner end of the screw-threaded shaft screws into and out of an internally-threaded bore formed in one end of a rod 38 so as to exert a push or pull upon the rod, the other end of this rod being pivotally connected to swing lever plates 39. The swing lever plates are secured at one end to the foot wing 10 of the frame 5 and at its other end to a bar 40, this bar being in turn pivotally connected to a strap 41 suspended from the cross-rod 32. Thus, by turning the crank 37 the cross-rod 32 may be shifted along the length of the slots 33 and thereby determine the character of the movement imparted to the terminal wing 10 when the latter is dropped or raised.

The hand-cranks 12 and 21 located at the foot of the bed are adapted to be moved to out-of-the-way position. As shown in Fig. 3, the crank arm 12 has slidably associated with its outer end a collar 43 having a handle 44 projecting from one side thereof. This collar is normally coupled to the crank arm by means of a notch 45 on the outer edge of the collar engaging a pin 46 projecting from the crank arm. A coil spring 47 encircles the crank arm and bears at one end against a disk 48 abutting a stop lug 49 on the crank arm and at its other end against a disk 48a abutting the collar 43. The pressure of the spring 47 maintains the pin 46 in engagement with the notch 45. The interengaging notches 45 and pins 46 may be increased in number if desired.

When the hand crank is not in use, the collar 43 may be slid along the hand crank arm against the action of spring 47 to disengage the pin 46 from the notch 45 and the collar handle 44 is turned inwardly toward the bed into the dotted line position indicated in Fig. 3. The hand-crank 21 associated with shaft 20 is similarly constructed.

Associated with the bed is a bed-pan carrier K, more particularly illustrated in Figs. 4 through 8.

The bed pan carrier comprises a box-shaped housing 50 and a carrier arm 51 normally occupying a retracted vertical position within the housing when not in use. The housing of the bed pan carrier is supported by and between a pair of uprights 52 secured to the foot-end frame 2 of the bed, the upper ends of these uprights having pins 53 projecting into longitudinal slots 54 formed in the side walls of the housing. By virtue of this construction, the housing normally hangs freely between the uprights with the pins 53 abutting one end of the slots 54 (see Fig. 4) but when the bed pan is to be put into service the housing is swung upwardly about the pivot pins 53 into horizontal position and projected inwardly of the bed until the pins engage the lower ends of the slots, as best shown in Figs. 1 and 6. A sheet metal, channel-shaped brace

plate 55 is pivotally connected at its lower end, as at 56', to the uprights 52 and is adapted to be swung upwardly and outwardly of the end frame 2 so that its sides embrace the sides of the housing. Its outer end is provided with latches

57 designed to engage pins 56 on the housing and thereby firmly hold the housing in horizontal position during the time the pan carrier is in service.

The carrier arm 51 comprises a trough of V-shaped cross-section upon the outer end of which is mounted a platform 57a for receiving the bed pan P, while the inner end of the carrier arm enters the housing 50 and travels within a V-shaped slideway formed in a block 58, as shown in Fig. 7. Fixed to and closing the inner end of the carrier arm is a nut 59 having an internally threaded opening through which passes a screw-threaded operating shaft 60. This shaft is rotatably supported in a wall 61 closing the outer end of the housing, and to the end of this shaft projecting outwardly beyond the wall 61 is secured a hand-crank 62. Thus, by manually turning this hand-crank the operating shaft is rotated to move the nut 59 (and with it the carrier arm 51) inwardly and outwardly of the housing, the carrier arm providing clearance space within its trough for the operating shaft. The outer end of the carrier arm is preferably cut off at a slant as indicated at 51a.

When the bed-pan carrier is retracted (as indicated in dotted lines in Fig. 6) the top surface of the platform 57a lies in a plane with the top surface of the housing cover indicated at 50b. This allows the bed pan to be grasped by the bed attendant and slid off the platform onto the cover of the housing, and thence along the cover to a position at the foot of the bed where it may be conveniently removed.

To avoid accidental tipping of the bed pan P when in use, it is provided upon its bottom with a recessed trackway 63 of such gage as to snugly fit over and embrace the sides of the platform 57a and housing cover 50b, as more clearly shown in Fig. 8. The pan is locked to the platform by means of a pivoted latch 64 on the platform arranged to project into an opening in the pan. The latch is so located as to strike the housing cover and be moved to release position when the carrier arm is fully retracted.

The operation of the invalid bed just described is as follows:

By operating the hand cranks 12 and 21 the head wing 7 and the movable intermediate wing 9 and terminal wing 10 may be swung either upwardly or downwardly from a horizontal plane. And, as has been already explained, by turning the crank 37, the links 30 are adjusted along the slots 33 so as to determine the angular relationship of the terminal wing 10 with respect to the movable intermediate wing 9. As indicated in Fig. 2, the range of adjustment of the wings is quite wide so as to accommodate the bed to practically any position of repose that the occupant may desire.

This flexibility of adjustment is especially desirable in those cases where the patient must wear casts or splints which restrict his freedom of movement and often require that he be supported in unusual and awkward positions as an aid for which the ordinary adjustable bed is either unsatisfactory or wholly inadequate.

When the bed pan P is to be used by the patient, the hand-crank 21 will be operated by the bed attendant in a manner which already has

been explained, so as to drop the movable intermediate wing 9 and terminal wing 10, thus lowering the limbs of the patient while allowing the greater part of his weight to rest on the fixed intermediate wing 8.

Next the bed pan is latched onto the platform 57a of the carrier arm 51 and the housing 50 is swung from vertical to horizontal position and simultaneously shifted forwardly of the bed to the limit allowed by the slots 54, the brace plate 55 then being latched to the outer end of the housing to maintain the latter solidly in place. By turning the crank 62, the bed attendant is enabled to project the bed pan (under the bed covers) into generally the position shown in Fig. 1; that is, with the top of the bed pan lying approximately in the same plane with the top of the mattress M overlying the fixed intermediate wing 8 and the patient in straddling relation thereto. The bed attendant now turns the crank 12 so as to elevate the head wing 7 which raises the patient to full or partial sitting position and at the same time slides him gently forward onto the bed pan. The inclined outer end of the carrier arm abuts and presses against the sloping surface of the mattress overlying the movable intermediate wing 9, as a consequence of which the pan is held firmly in place.

After use, the bed pan is withdrawn into a position accessible by the bed attendant by again turning the crank 62, but in the reverse direction, so that when the platform 57a abuts the housing 50, the latch 64 is automatically released so that the pan may be slid off the platform onto and along the runway of cover 50b, where it may be readily removed by the attendant.

Of course, the adjustment of the patient to the bed pan may be carried out in other ways than that just described. For example, it is not necessary that the head wing be raised, but the pan may be employed with the patient in substantially horizontal position with the wings 9 and 10 dropped only sufficiently to admit the pan between the patient and the mattress. The proper positioning of the patient will depend upon the circumstances surrounding each case, and my bed offers a wide flexibility of adjustment to meet unusual situations.

It will be seen that I have provided an invalid bed of comparatively simple and inexpensive construction and which is convenient and expeditious in operation. An important advantage of this bed lies in the fact that no special form of mattress, sheets, pads or rubberized coverings are required to be employed in conjunction with the bed such as is the case with many invalid beds that have been heretofore proposed, and furthermore it is not necessary to expose the patient to drafts by raising the bed covers when introducing and withdrawing the bed pan.

With the form of invalid bed just described the patient may be placed in a lying position or a sitting position, or any degree of intermediate position, thus permitting him to use the bed pan in any of these positions; or when not using the pan to assume any desired position suited either to his comfort or expediency.

When the bed pan is not in use, and the patient wishes to sit up, as while dining or during convalescence, this may be accomplished simply by raising the head wing and lowering the terminal wing of the mattress support in the manner heretofore described. It is not necessary to remove the patient from the bed, and a nurse

can readily handle the heaviest patient without calling in extra help.

It is to be understood that the invalid bed described and illustrated herein is to be regarded as illustrative and not restrictive of the invention since various changes may be made by one skilled in the art without departing from the spirit and scope of the invention as defined by the appended claims.

I claim:

1. An invalid bed comprising a head-end frame, a foot-end frame, side rails extending between said frames, a sectional mattress support located between the side rails, said mattress support including a wing located intermediate the length of the mattress support fixed in substantially horizontal position, a movable wing located between the fixed wing and the foot-end frame, said movable wing being pivoted at its end adjacent the fixed wing for swinging movement, means for raising and lowering the movable wing into and out of a horizontal position, a carrier arm adapted to support a bed pan at its outer end mounted upon the foot-end frame, and means for extending and retracting said arm in a horizontal plane into and out of a position above and adjacent the elevated end of the movable wing to enable its outer end to abut a mattress overlying said wings.

2. An invalid bed comprising a head-end frame, a foot-end frame, side rails extending between said frames, a sectional mattress support located between the side rails, said mattress support including a wing located intermediate the length of the mattress support fixed in substantially horizontal position, a movable wing located between the fixed wing and the foot-end frame, said movable wing being pivoted at its end adjacent the fixed wing for swinging movement, means for raising and lowering the movable wing into and out of a horizontal position, a bed-pan carrier mounted on the foot-end frame of the bed, said carrier comprising a housing swingable from a vertical to a horizontal position, a carrier arm adapted to be received within said housing and adapted to support a bed pan at its outer end, and means for projecting said arm from said housing into a position above and adjacent the elevated end of the movable wing to enable the outer end of the arm to abut a mattress overlying said wings.

3. An invalid bed comprising a head-end frame, a foot-end frame, side rails extending between said frames, a sectional mattress support located between the side rails, said mattress support including a wing located intermediate the length of the mattress support fixed in substantially horizontal position, a movable wing located between the fixed wing and the foot-end frame, said movable wing being pivoted at its end adjacent the fixed wing for swinging movement, means for raising and lowering the movable wing into and out of a horizontal position, a bed-pan carrier mounted on the foot-end frame of the bed, said carrier comprising a housing pivotally mounted so as to be swung from a vertical to a horizontal position, a carrier arm adapted to be received within said housing and adapted to support a bed pan at its outer end, a screw-threaded operating shaft rotatably mounted upon said housing and threadedly engaging said arm, and a crank for turning said operating shaft for extending and withdrawing said arm from and into said housing whereby the outer end of said arm is

adapted to occupy a position adjacent the elevated end of the movable wing and abut a mattress overlying said wings.

4. An invalid bed comprising a head-end frame, a foot-end frame, side rails extending between said frames, a sectional mattress support located between the side rails, said mattress support including a wing located intermediate the length of the mattress support fixed in substantially horizontal position, a movable wing located between the fixed wing and the foot-end frame, said movable wing being pivoted at its end adjacent the fixed wing for swinging movement, means for raising and lowering the movable wing into and out of a horizontal position, a bed-pan carrier mounted on the foot-end frame of the bed, said carrier comprising a housing mounted so as to be swung from a vertical to a horizontal position and thence inwardly toward the head-end frame, a carrier arm slidably receivable within said housing and adapted to support a bed pan on its outer end, a nut secured to said arm, a screw-threaded operating shaft rotatably mounted upon said housing and threadedly engaging said nut, and a crank for turning said operating shaft for projecting said arm from and retracting it into said housing whereby the outer end of said arm is enabled to occupy a position adjacent the elevated end of the movable wing and abut a mattress overlying said wings.
5. An invalid bed comprising a head-end frame, a foot-end frame, side rails extending between said frames, a sectional mattress support located between the side rails, said mattress support including a wing located intermediate the length of the mattress support fixed in substantially horizontal position, a movable wing located between the fixed wing and the foot-end frame, said movable wing being pivoted at its end adjacent the fixed wing for swinging movement, means for raising and lowering the movable wing into and out of a horizontal position, a bed-pan carrier mounted on the foot-end frame of the bed, said carrier comprising a housing mounted so as to be swung from a vertical to a horizontal position and thence inwardly toward the head-end frame, a carrier arm slidably receivable within said housing, said arm being of trough shape, a nut secured to said arm, a screw-threaded operating shaft rotatably mounted upon said housing and threadedly engaging said nut, said shaft extending within the trough of the arm, a crank for turning said operating shaft for horizontally projecting said arm from and retracting it into said housing, whereby the outer end of the arm is enabled to occupy a position adjacent the elevated end of the movable wing and abut a mattress overlying said wing, and a platform mounted upon the outer end of said arm and providing a tongue-and-groove connection with a bed pan for retaining said pan in association with the platform.
6. An invalid bed comprising a head-end frame, a foot-end frame, side rails extending between said frames, a sectional mattress support located between the side rails, said mattress support including a wing located intermediate the length of the mattress support fixed in substantially horizontal position, movable wings pivoted adjacent the forward and rear ends of the fixed wing, means for swinging said wings out of a horizontal plane for moving the patient occupying the bed from a reclining to a sitting position, a bed-

pan carrier mounted on the foot-end frame of the bed, said carrier comprising a housing mounted so as to be swung from a vertical to a horizontal position and thence inwardly toward the head-end frame, a carrier arm slidably receivable within said housing and adapted to support a bed pan on its outer end, a nut secured to said arm, a screw-threaded operating shaft rotatably mounted upon said housing and threadedly engaging said nut, and a crank for turning said operating shaft for projecting said arm from and retracting it into said housing whereby the outer end of said arm is enabled to occupy a position adjacent the rear end of the fixed wing and abut a mattress overlying said wings.

7. A bed-pan carrier comprising a housing having a cover and adapted to be attached to the foot-end frame of a bed, a carrier arm receivable within the housing, a platform mounted upon the outer end of the arm for supporting a bed pan, means upon the platform for attaching a bed pan thereto, a nut secured to the arm, a screw-threaded operating shaft rotatably mounted upon the housing and having threaded engagement with the nut and a crank for rotating the shaft to project the arm from and retract it into the housing, said platform in the retracted position of the arm having its upper surface lying substantially co-extensive with the cover of the housing to facilitate removal of the bed pan from the platform onto and along said cover.

8. In an invalid bed comprising head and foot frames, side rails connecting the same, a sectional mattress support having a fixed wing secured to the side rails and an intermediate wing pivoted to the fixed wing, a foot wing pivoted to the free end of the intermediate wing and

means for adjusting the inclination of said foot wing relative to the fixed wing; the combination of an adjustable bed pan support positioned over the foot wing of the mattress support, comprising a housing having longitudinal slots in its side walls, a bed pan carrier arm slidably mounted in the housing, a threaded shaft carried by said housing engaging the carrier arm, whereby the same is adjusted, uprights secured to the bed foot frame having pins engaging in the slots of the bed pan supporting housing and a brace plate pivoted to the uprights in locking engagement with the housing, whereby it is held in functioning position.

15. 9. In an invalid bed comprising head and foot frames, side rails connecting the same, a sectional mattress support having a fixed wing secured to the side rails, an intermediate wing hinged at one end to the fixed wing and a foot wing hinged to the other end of the intermediate wing, the foot wing being provided with longitudinal slots in juxtaposition to its pivoted connection with the intermediate wing; the combination of means for raising and lowering 20 the connected intermediate and foot wings comprising a cross rod engaging the foot wing slots, a strap depending from the cross rod, a swinging lever plate pivoted to the foot wing, a bar pivotally connecting the cross rod strap and swinging lever 25 plate, a threaded rod carried by the foot wing and connected to the swinging lever plate for manually shifting the cross rod in the foot wing slots, a transversely disposed shaft positioned under said foot wing, anchored on the side rails, 30 arms carried by the shaft, links pivotally connected to foot wing and arms, and other links pivotally connecting said arms and cross rod.

35

ANTON DISHMAKER.
